UNITED STATES PATENT OFFICE.

JOHN R. BOONE, OF NASHVILLE, TENNESSEE.

HYDROCARBON-BURNER.

No. 810,283.

Specification of Letters Patent.

Patented Jan. 16, 1906.

Application filed June 24, 1905. Serial No. 266,741.

To all whom it may concern:

Be it known that I, JOHN R. BOONE, a citizen of the United States, residing at Nashville, in the county of Davidson and State of Tennessee, have invented certain new and useful Improvements in Hydrocarbon-Burners, of which the following is a specification.

My invention relates generally to hydrocarbon-burners adapted to heat water to generate steam to propel engines used for driving automobiles, launches, and other vehicles.

More particularly, the invention relates to that class of burners in which an initial burner is employed in starting to vaporize the gasolene or other fuel supplied to the pilot or subburner, which in turn heats the vaporizer through which the gasolene or other fuel passes to the main burner. In burners of this class the initial burner is only used when starting, which latter serves to vaporize the fuel for the pilot or subburner, which is kept constantly burning and serves not only to vaporize the fuel for the main burner, but also to maintain sufficient heat to keep up steam at a low pressure in the boiler when the supply of fuel in the main burner is suspended.

The object of my invention is to simplify the construction of such burners, render their adjustment easy, and make them readily removable or separable for inspection or repair.

In carrying out my invention I permanently attach the case of the subburner to a suitable part of the main burner, and the subburner and initial burner are separable from the case, so that they may be readily withdrawn for inspection, adjustment, or repair. The subburner is also readily detachable from the fuel-supply pipe, and the spraying-nozzle is easily accessible or may be easily removed. The initial burner is in the form of a cup which surrounds the lower member of the subburner, and this is arranged to heat a coil which surrounds the upper portion of the upper member of the subburner and which is made readily detachable from the subburner and from the supply-pipe. The fuel which supplies the nozzle of the subburner passes through the coil.

In the accompanying drawings, Figure 1 is a perspective view of a steam-generator and main burner of well-known construction with my improved subburner and its accessories applied. Fig. 2 shows a vertical central sec-

tion of the same. Fig. 3 is a detail view in perspective, showing particularly how the casing of the subburner is permanently attached to the main burner and how the subburner and its accessories are removable from the casing. Fig. 4 shows a vertical central section through the subburner and parts connected therewith.

I have shown my improvements applied to a main burner and generator of a well-known kind.

A indicates the coil of water-pipe of the generator, and B the main burner for heating it. This burner is shown as consisting of a chambered plate having on its upper side annular perforated ribs b, through which the vaporized fuel passes. The vaporizer C is also of well-known construction. This vaporizer is connected with the interior of the burner B by a pipe c and with the fuel-supply pipe D by a pipe c'. A valve d controls the admission of fuel to the vaporizer C.

My improved subburner is contained within a case E, permanently attached to the main burner. This case is preferably cylindrical and at its lower end on diametrically opposite sides is formed with right-angled slots e to receive the stud e' of the subburner, with which it forms a bayonet-joint. The subburner has two principal parts F and G, which I call the "upper" and "lower" members. The lower member F has a central vertical passage f through it, and at its upper end it carries a spraying-nozzle H. The supply of fuel through the passage f is controlled by a needle-valve h, and the fuel passes to the passage f, through a channel f', extending diagonally upward through a boss K. Surrounding the central portion of the lower member is a cup I, which constitutes the initial burner and to which fuel is supplied through the channel f', passage f, and nozzle H in the manner hereinafter explained. The upper member G comprises a tubular stem g and an upper enlargement, head, or cup g', into which the fuel is sprayed and which contains a spreader J. The upper member G is supported on a yoke L. Its tubular stem g fits tightly in the top of the yoke, and the yoke has an annular bottom portion l, which rests on the cup I and which is connected with the top portion by uprights l'. The lower member F is clamped to the cup I by means of a nut I', and when so clamped the yoke L is held firmly in place by reason of the engagement of the boss K with the base l of

the cup I.

the yoke in the manner indicated in Figs. 3 and 4.

The cup I is provided with a tubular threaded boss M, which is adapted to be connected with the fuel-supply pipe, and this threaded boss connects with another boss N above it, which has a detachable connection with one branch o of a coil O. The other branch o' has a detachable connection with the tubular boss K. The coil O surrounds the spreader J above the subburner.

Normally the subburner and its accessories are contained within the case E and locked thereto in the manner indicated in Figs. 1 and 2; but, if desired, by merely uncoupling the threaded boss M from the supply-pipe N' the subburner may be detached from the casing by turning the studs e' in the slots e and separating the parts in the ordinary way of operating a bayonet-joint. While I have shown a bayonet-joint, other connections may be used. When the burner is thus detached, it may be cleaned, inspected, or repaired. The coil O may be easily detached by uncoupling the unions o². The nozzle H may obviously be easily detached and, if necessary, thrown away and replaced by a new one, or the old nozzle may be easily cleaned.

When starting up for the first time, the valve d may be closed and the valve h is opened, so that fuel may pass through the boss M, coil O, passage f' and f, and through the nozzle H. The fuel which at this time passes through the nozzle is not vaporized, but flows over into the cup I. When this fuel is ignited, it heats the fuel in the coil O and vaporizes it, so that thereafter the fuel that emerges from the nozzle H is in the form of a vapor and as such burns at the spreader J. Preferably after the cup I is supplied with a sufficient amount for the initial burner the valve h is closed and the fuel in the cup I ignited, so as to heat properly the fuel in the coil O. Then the valve h may be opened and the fuel in the form of a vapor and under pressure will emerge from the nozzle H and ignite. Thereafter the fuel passing through the coil O is heated by the subburner, the initial burner of course being no longer employed. The subburner heats the vaporizer C, that supplies the main burner. The main burner

may be shut off from time to time, while the subburner is kept constantly burning and maintains vapor in the vaporizer C, so that the vehicle may be started up quickly whenever desired. 55

By my improvements I have produced a very efficient subburner and one which is extremely simple and may be applied to various kinds or types of main burners. 60

It will be observed that only one valve is employed to regulate the subburner, and the parts are readily detachable and may be cleaned, repaired, or replaced with great facility. 65

I claim as my invention—

1. The combination of a main burner, a casing open at the bottom and permanently attached to the main burner, a cup constituting an initial burner and having a detachable connection with the casing at its lower end, the lower member of the subburner detachably connected with the cup, and carrying a spraying-nozzle, the upper member of the subburner, means for supporting it on the cup or initial burner, a coil surrounding the upper member, and connected with the spraying-nozzle, a fuel-supply passage with which the coil is also connected, and a fuel-supply pipe detachably connected with the coil, the arrangement being such that all parts of the subburner are supported on the cup or initial burner and are detachable therewith and removable together through the bottom of the fixed casing. 70 75 80 85

2. The combination of the lower member of the subburner, a cup or initial burner surrounding it and detachably connected therewith, the upper member of the subburner, the yoke resting on the cup clamped thereto and supporting the upper member, a nozzle between the two members, a vapor-coil surrounding the burner, a supply-pipe to which the coil is detachably connected, a boss on the lower member of the burner and a detachable connection between the boss and the coil. 90 95

In testimony whereof I have hereunto subscribed my name.

JOHN R. BOONE.
